FLUID PRESSURE MOTOR

Filed April 14, 1944

UNITED STATES PATENT OFFICE

2,397,778

FLUID-PRESSURE MOTOR

Fred E. Cooper, Los Angeles, Calif.

Application April 14, 1944, Serial No. 530,977

8 Claims. (Cl. 121—164)

My invention relates to a fluid pressure motor of the multi-cylinder type and has for its principal object, to provide a motor comprising an elongated cylinder formed in sections, each section having a piston chamber with a piston therein and a piston rod carrying said pistons and arranged to reciprocate axially within the cylinder, such form of motor being particularly intended for the efficient operation of deep well pumps.

Further objects of my invention are, to provide in a multi-cylinder motor, new and novel joints between the cylinder sections, which joints include means providing bearings for the reciprocating piston rod and further, to provide a simple and efficient arrangement of ducts, for conveying fluid pressure to all of the piston chambers and the exhaust of expended pressure therefrom, which ducts extend lengthwise through the walls of the cylinder sections and the joints between same.

A further object of my invention is to provide a multi-cylinder motor of the character referred to, wherein the diameter of the elongated body of the motor, composed of an in-line series of cylinders, is minimized, in order that the motor may be advantageously employed in connection with the pumps of deep wells having tubes or casings of small diameters.

With the foregoing and other objects in view, my invention consists in certain novel features of construction and arrangement of parts, which will be hereinafter more freely described and claimed and illustrated in the accompanying drawing, in which:

Fig. 1 is a longitudinal section through the center of a motor constructed in accordance with my invention, with parts broken away.

Fig. 2 is a vertical section taken on the line 2—2 of Fig. 1.

Fig. 3, is an enlarged horizontal section taken on the line 3—3 of Fig. 2.

Fig. 4 is an enlarged horizontal section taken on the line 4—4 of Fig. 2.

Fig. 5 is a perspective view of one of the joint members.

Fig. 6 is a vertical section taken on the line 6—6 of Fig. 5.

Fig. 7 is a vertical section taken on the line 7—7 of Fig. 5.

Fig. 8 is an enlarged detail section taken on the line 8—8 of Fig. 7.

Fig. 9 is a vertical section taken on the line 9—9 of Fig. 7.

Referring by numerals to the accompanying

drawing which illustrates a preferred embodiment of my invention, 10, 11 and 12 designate the three upper sections of the motor body, which sections are formed of metal tubing of suitable length and diameter.

The body may be composed of an indefinite number of sections and thus the complete motor may have a length of ten or twenty feet, with a diameter of from three to eight or more inches which enables said motor to be conveniently used in well pipe or casing of small diameters.

Upper section 10 of the motor body, which differs somewhat from the identical lower sections 11 and 12, is closed at its upper end by a cap 13 carrying a bail 14, by means of which the motor is suspended, raised and lowered and passing through a gland 15 in the top of said cap, is a fluid pressure supply pipe 16.

Formed in the side wall of cap 13 and the upper portion of the wall of tube section 10 are coinciding apertures which provide an exhaust port 17. Screw seated in the upper portion of section 10 is a plug 18, through which is formed a fluid pressure inlet duct 19, with which duct 16 connects. The space within section 10 below plug 18 serves as a fluid pressure chamber 20.

The upper and lower portions of plug 18 on one side thereof are cut away thus leaving an intermediate cylindrical portion 21 and formed in the upper half of the latter is a pair of exhaust ducts 22 which extend upward through the upper portion of the plug with their open ends located on the flat vertical face of said plug above the intermediate portion 21. Thus the inner ends of these ducts 22 communicate with the exhaust chamber 23 in section 10 between cap 13 and plug 18.

Fluid pressure ducts 24 are formed in the lower half of the intermediate portion 21 of the plug, which ducts extend downward through the lower portion of said plug with their open inner ends located on the flat vertical face of plug 18 below portion 21.

The open inner ends of the ducts 22 and 24 just described, function as ports and mounted for reciprocating movement on the flat faces of the plug above and below intermediate portion 21 is a slide valve 25 which controls said ports so as to simultaneously open one of the pressure inlet ports and close one of the exhaust ports.

Valve 25 is held for sliding movement by flanges 26 on the flat vertical faces of plug 18, there being sufficient friction between said valve and

flanges, to prevent said valve from sliding downward by gravity.

Connected to said valve is a depending rod 26 having spaced threaded portions 27, on which are screw seated nuts 28, the same providing abutments adapted to be engaged by a finger 29 and the latter being adjustably mounted on the upper portion of a piston rod 30.

Thus the slide valve 25 is actuated to alternately open and close the inlet and exhaust ports, such action taking place at the termination of the reciprocating strokes of the piston rod.

A guire 31, either on the piston rod or tube 10 may be provided for the lower portion of rod 26.

Piston rod 30 passes axially downward through those tube sections including sections 11 and 12 which form the body of the motor and through cylindrical joint members such as 32 which connect the ends of said sections.

The lower end of piston rod passes through a gland or stuffing box at the lower end of the lowermost tube section and is suitably connected to a pump rod.

The space within each section of the body provides a piston chamber 33 and carried by the piston rod within each chamber, is a piston such as 34 arranged in the lower portion of each joint member 32 and surrounding the piston rod is a gland or stuffing box 35.

Each joint member 32 comprises a short cylindrical body externally threaded so that it may be screw seated in the adjacent ends of tube sections such as 10 and 11 or 11 and 12 and screw seated on each member between the ends of the tube sections are lock rings or nuts 36, having recesses 37 for the reception of a spanner wrench and as illustrated in Fig. 1 the ends of these lock nuts and the ends of the tube sections may be correspondingly countersunk and chamfered.

Leading downward from the top of each joint member 32 is a pair of pressure inlet ducts 38, which terminate near the lower end of said member and leading outward from each duct near its upper and lower ends are short horizontally disposed branch ducts 39.

Similar ducts 40, which function for the exhaust of fluid pressure from the piston chambers, extend upward from the bottom of the joint member to a point near the top thereof and leading from each exhaust duct outwardly near the top and bottom of said body are branch ducts 41 (see Figs. 5 and 6).

Formed in the outer faces of all of the tube sections of the motor are four longitudinally disposed grooves, two of which 42, function as fluid pressure supply ducts and the other two 43, provide exhaust ducts.

Overlying each duct and secured to the tube by welding or otherwise is a metal strip 44 which provides a cover plate and formed through the ends thereof and communicating with the end of the covered duct and the outer end of the corresponding branch duct (39 or 41) is an aperture 45.

This aperture enables a short tubular member such as 46 to be screw seated in the wall of strip 44 and in the underlying branch duct and after said tubular member has been thus seated, a cap plate such as 47 is welded to strip 44 over said aperture 45.

The arrangement of ducts just described provides for the conduction of fluid pressure from pressure chamber 20 downward successively through the ducts 42 in all the sections of the

motor body and through ducts 38 in joint members 32, to act on the pistons 34, also for the exhaust pressure to pass through ducts 43 in the motor sections and through ducts 40 in said joint members, to chamber 23 and exhaust outlet 17.

As fluid pressure enters the piston chamber above the pistons therein, the latter are driven downward and the spent fluid pressure beneath the pistons passes out and upward to exhaust chamber 23 and thence to atmosphere through port 17.

The flow of fluid pressure to the ducts which lead to the piston chambers and the exhaust of spent pressures from said chambers, is controlled by the slide valve 25 and the timing of the latter is controlled by the piston rod as the latter approaches and reaches the end of its travel.

The formation of the motor body in sections, enables a motor of any desired length to be produced and the arrangement whereby the fluid pressure and exhaust ducts are formed by grooving the body sections, enables the highest grade tubing to be utilized in the building of the motor, with a material reduction in production costs as compared to construction involving special castings and patterns therefor.

Thus it will be seen that I have provided a multi-cylinder motor especially adapted for the operation of deep well pumps and which motor is simple in construction, inexpensive of manufacture and very effective in performing the functions for which it is intended.

It will be understood that minor changes in the size, form and construction of the various parts of my improved motor may be made and substituted for those herein shown and described without departing from the spirit of my invention, the scope of which is set forth in the appended claims.

40 I claim as my invention:

1. In a fluid pressure motor, an elongated body comprising a series of axially aligned cylinders, a piston bearing rod passing through said cylinders, each cylinder being provided in the outer face of its wall with a plurality of longitudinally disposed ducts, cover strips secured to the outer faces of said cylinders over said ducts, joint members connecting the adjacent ends of said cylinders which joint members are provided with ducts which communicate with the ducts in said cylinders and with the chambers within said cylinders between said joint members, and plugs screw-seated in said cylinders, and joint members between the ends of the ducts therein.

55 2. A fluid pressure motor as set forth in claim 1 and with valvular means actuated by said piston rod for controlling the flow of fluid pressure and the exhaust of spent fluid pressure through said ducts.

60 3. A fluid pressure motor as set forth in claim 1 with the ends of said cylinders being bevelled and lock nuts screw seated on said joint members between the ends of said cylinders the ends of which lock nuts are countersunk for the reception of the bevelled ends of said cylinders.

65 4. In a fluid pressure motor a hollow cylinder provided in the outer face of its wall with longitudinally disposed fluid pressure and exhaust ducts cover strips secured to said cylinder and overlying the ducts therein and plugs closing the ends of said cylinder, which plugs are provided with fluid pressure and exhaust ducts which communicate respectively with the fluid pressure and exhaust ducts in said cylinder.

70 5. In a fluid pressure motor, a series of axially

aligned cylinders, joint members connecting the ends of said cylinders, the walls of which cylinders are provided in their outer faces with longitudinally disposed fluid pressure inlet and exhaust ducts, cover strips secured on the outer faces of said cylinders over the ducts therein, said joint members provided with inlet and exhaust ducts which communicate with the corresponding ducts in said cylinder screw-plugs seated in the walls of said cylinders and said joint members at the points of communication between the ducts therein, a cylinder at the upper end of the series of connected cylinders, provided with a compressed fluid chamber and an exhaust chamber, valvular means arranged for operation between said compressed fluid chamber and exhaust chamber for controlling the flow of fluid pressure to and through the ducts in said cylinders and joint members, and a piston rod extending axially through said cylinders and joint members.

6. The fluid pressure motor as set forth in

20

claim 5 and means for actuating said valvular means at the ends of the travel of said piston rod.

7. The fluid pressure motor as set forth in claim 5 with the ends of said cylinder being bevelled and lock nuts located on said joint members between the ends of said cylinders the ends of which lock nuts are countersunk for the reception of the bevelled ends of said cylinders.

10 8. In a fluid pressure motor a cylinder, provided in its outer face with longitudinally disposed channels, cover strips secured to the outer face of the cylinder and overlying said channels plugs seated in the ends of said cylinder, which plugs are provided with ducts which communicate with the channels in said cylinder, and tubular plugs screw-seated in said cylinder and plugs at the points of communication between said channels and ducts.
